UNITED STATES PATENT OFFICE.

JESSE W. REES, OF ST. PAUL, MINNESOTA.

JACK.

1,172,832.

Specification of Letters Patent. Patented Feb. 22, 1916.

Application filed March 23, 1914, Serial No. 826,759. Renewed July 1, 1915. Serial No. 37,588.

To all whom it may concern:

Be it known that I, JESSE W. REES, a citizen of the United States, residing at St. Paul, in the county of Ramsey and State of Minnesota, have invented a new and useful Improvement in Jacks, of which the following is a specification.

The object of my invention is the production of a lifting jack of that character which is portable and adapted for lifting heavy loads with little effort.

This invention relates to that class of lifting jacks in which a rack member carrying a head is vertically movable in a suitable base.

More particularly this invention provides a lifting jack in which power is applied equally on opposite sides of the rack member whereby resistance is reduced in applying a lifting effort.

This invention also provides in combination with the elements specified, means for engaging a car wheel or its equivalent to hold it stationary while the lifting effort is applied to a journal box in which the wheel is mounted.

Further details of improvement will be apparent from the following description, and more particularly pointed out in the claims.

In the accompanying drawings, Figure 1 is a vertical section of my invention, the section being taken on the line X—X, Fig. 3; Fig. 2 is a section taken on the line Y—Y of Fig. 1; Fig. 3 is another vertical section taken on the line Z—Z of Fig. 2; Fig. 4 is an end view partly broken away and in section of the ratchet mechanism for revolving the drive shaft; Fig. 5 is a side elevation of my invention illustrating its application in use for raising a journal box for a car wheel, and Fig. 6 is a plan partly in section of the adjustable stop on the jack.

My invention is composed of three main elements, a base A, a head B, which is carried by the base and adapted to raise and lower, and a stop C which is also carried by the base.

The base A is in the form of a substantially vertical housing having four substantially flat sides 2, 3, 4 and 5 forming an enclosure, the upper end of said housing being open and the lower end closed by a floor 6 integral with said sides. Placed in the housing are two opposite vertical channel members 7 and 8, each of which is in the form of

a vertical plate having its side edges turned in to produce two oppositely disposed channels 9 and 10, said edges being spaced apart to form a vertical passage 11. The channel members 7 and 8 are of similar construction, the passages 11 being disposed facing each other and their plates lying flat upon the sides 2 and 3 of the housing as illustrated. Disposed in the channels 9 and 10 of each channel member are pinions 12 and 13, which are free to turn between the sides of said channels, there being two pinions 12—12 placed in the channels 9—9 in axial alignment and two pinions 13—13 in axial alignment in the channels 10—10 of the two channel members. There is a shaft 14 provided, upon which the pinions 12—12 are mounted and a shaft 15 upon which the pinions 13—13 are mounted, whereby the pinions upon each shaft are driven simultaneously. The shafts 14 and 15 are journaled in the plates and inturned ends of the channel members, suitable journal openings being provided for that purpose. Passing freely across the housing between the channel members 7 and 8 and journaled in the journal bearings 16 and 17 formed on the sides 4 and 5 is a drive shaft 18. This shaft carries a pair of right and left handed worm pinions 19 and 20, which respectively mesh with worm gears 21 and 22. These worm gears are respectively mounted upon the shafts 14 and 15, whereby, as the shaft 18 is revolved, the pairs of pinions 12—12 and 13—13 are turned in opposite directions.

The drive shaft 18 is revolved in either direction by turning the wheel 23 which is journaled freely on the shaft 18, and carries a freely pivoted dog 24, said dog being adapted to engage the teeth of a ratchet wheel 25 keyed securely upon said shaft. The wheel 23 is provided with a series of openings 26 in its periphery, in any one of which the end of a lever handle such as 27 (see Fig. 4) is adapted to be inserted to revolve the wheel. The ratchet wheel 25 on one end of the shaft 18 and a collar 28 secured on the opposite end hold the shaft longitudinally in the housing. The pinions 19 and 20 being right and left handed relieve the shaft 18 from end thrust in the application of power to the worm pinions.

The head B by which a lifting effort is imparted is formed with a bifurcated shank 29. The members 30 and 31 forming the bifurcations respectively consist of a double

rack having sets of teeth 32 and 33. The oppositely disposed sets of teeth on each rack member, are adapted to mesh with the teeth of the respective pairs of pinions 12-12 and 13-13, so that as said pinions are revolved in opposite directions simultaneously as described, the head is either raised or lowered. Each rack member is formed with a broad rib 34 on its inner side 10 wall which is adapted to slide vertically in the passage 11 in the channel member in which the rack member is mounted. When the pinions 12-12 and 13-13 are revolved, power is applied equally on the opposite 15 sides of the racks, thus minimizing lateral effort and resistance which would otherwise be increased if power were applied only to one side of each rack. It will be noted that the load on the head B is carried by the 20 channel members in the housing, and that the channel members and the parts which are directly mounted thereon being articulated from the balance of the mechanism can very easily and quickly be lifted out of 25 the housing for the purpose of lubricating and cleaning the working parts and reassembling the mechanism.

In accordance with the patent statutes, I have described the principles of operation 30 of my invention together with the apparatus which I now consider to represent the best embodiment thereof but I desire to have it understood that the construction shown is only illustrative and that the invention can be carried out by other means 35 and applied to uses other than those above set forth within the scope of the following claims.

Having described my invention, what I 40 claim as new and desire to protect by Letters Patent is:—

1. A lifting jack, comprising, in combination, a base element, a shaft journaled in said base element, gear mechanism adapted 45 to be driven by said shaft, means for revolving said shaft and a lifting head element formed with a bifurcated shank, each of the arms of said shank being formed with a set of rack teeth on opposite faces 50 thereof, adapted to mesh with said gear mechanism to apply a lifting effort to the opposite sides of each of said bifurcations simultaneously.

2. A lifting jack, comprising, in combination, a base element, a driving shaft journaled in said base element, means for revolving said shaft, gear mechanism adapted to be actuated by said shaft, articulated 60 supporting means removably seated in said base element and upon which part of said gear mechanism is journaled and permitted to be separated from connection with said drive shaft, and a lifting head element having a bifurcated shank, each of the bifurcations being formed with a pair of oppo-

sitely disposed sets of rack teeth adapted to mesh with the teeth of said gear mechanism, whereby a lifting effort is applied to the opposite sides of each of the bifurcations of said head element.

3. A lifting jack comprising a base, a lifting element having a bifurcated shank slidably mounted in said base, each of the arms of said shank being provided with rack teeth on its opposite sides, the adjacent faces 70 of said arms being reduced, channel members disposed within said base and coöperating with the reduced faces of said arms to guide said lifting element in its reciprocal movements, a shaft journaled in said base, and mechanism adapted to be driven by said shaft and engaging the rack teeth on said arms to raise said lifting element.

4. A lifting jack comprising a base, spaced rectangular members disposed within and extending throughout the height and longitudinal depth of said base, said rectangular members being provided with vertical passage-ways opening toward one-another, a lifting element having a bifurcated shank, 80 the adjacent faces of the arms of which are reduced to coöperate with the passage-ways in said rectangular members for guiding said lifting element in its reciprocal movements, each of the arms of said shank being 90 provided with rack teeth on its opposite sides, a shaft journaled in said base, and mechanism adapted to be driven by said shaft and engaging the rack teeth on said arms to raise said lifting element.

5. A lifting jack comprising a base, spaced rectangular members disposed within and extending substantially throughout the height and longitudinal depth of said base, said rectangular members being provided with vertical passageways opening toward one-another, a lifting element having spaced arms disposed within said rectangular members, the adjacent faces of said arms having reduced portions adapted 100 to slide within the passage-ways in said rectangular members to guide said lifting element in its reciprocal movements, each of the arms being provided with rack teeth on its opposite sides, a pair of spaced shafts journaled in and extending transversely across 110 said rectangular members, pinions carried by said transverse shafts within said rectangular members and meshing with the rack teeth on said arms, worm gears carried by said transverse shafts between said rectangular members, and a longitudinal shaft journaled in said base between said rectangular members having right and left hand worms thereon engaging said worm gears for driving 115 said transverse shafts.

6. A lifting jack comprising a housing, a lifting element having a bifurcated shank reciprocably mounted in said housing, spaced members within said housing for 120

125

130

- guiding said lifting element in its reciprocal movements, each of the arms of the bifurcated shank being formed with a set of rack teeth on opposite faces thereof, gear 5 mechanism meshing with the rack teeth on the opposite sides of said arms, and a driving shaft journaled in said housing adapted to actuate said gear mechanism to raise said lifting element.
10. 7. A lifting jack, comprising, a base, a lifting element slidably supported by said base having a double set of rack teeth disposed on opposite sides thereof, a pair of gear elements between which said lifting element moves up and down, each of said gear elements comprising a gear having teeth in mesh with the teeth of the adjacent set of rack teeth and a spiral drive gear, and a drive shaft journaled in said base 15 having opposite threaded worm pinions in mesh with said driving spiral gears, whereby the turning of said drive shaft is adapted to impart a forceful lifting movement to said lifting element.
20. 8. A lifting jack, comprising, a housing, a lifting element slidably mounted in and guided by said housing having a shank formed with a pair of opposite sets of rack teeth, gear mechanism meshing with said 25 rack teeth on the opposite sides of said shank, worm pinions meshing with said gear mechanism and a drive shaft journaled in said housing adapted to actuate said pinions to effect the raising of said lifting element.
30. 9. A lifting jack, comprising, a reciprocable lifting element having a bifurcated shank, a housing provided with means by which said lifting element is guided in its reciprocation, each of the arms of said bifurcated shank being formed with a set of 35 rack teeth on opposite faces thereof, gear mechanism meshing with the rack teeth on the opposite sides of said arms, and a driving shaft journaled in said housing adapted 40 to actuate said gear mechanism to raise said lifting element.
45. 10. A lifting jack, comprising, a reciprocable lifting element, having a bifurcated shank, a housing with means by which said lifting element is guided in its reciprocation, each of the arms of said bifurcated shank being formed with a set of rack teeth on opposite faces thereof, sets of gear mechanism meshing with the rack teeth on the opposite sides of said arms, a worm pinion 50 in mesh with each of said sets of gearing, and a shaft journaled in said housing and upon which said pinions are mounted to be driven.
55. 11. A lifting jack, comprising, a housing, a lifting element slidably supported by said housing having a bifurcated shank, each of the arms of said bifurcated shank having a double set of rack teeth, a set of gear mechanism meshing with the teeth of each of 60 said sets of rack teeth and having a spiral drive gear, a drive shaft journaled in said housing and a pair of oppositely pitched worm gears carried by said shaft and in mesh to drive said sets of gearing and effect 65 the movement of said lifting element.
65. 12. A lifting jack, comprising, a housing, a lifting element slidably supported by said housing having a bifurcated shank, each of the arms of said bifurcated shank having a double set of rack teeth spaced apart, sets of gears journaled in said housing having pinions of each set meshing with the teeth of said sets of rack teeth on said arms and a spiral gear carried by each of said sets 70 of gears, a drive shaft journaled in said housing and traversing the space between said rack teeth and oppositely pitched worm pinions on said shaft and meshing with the spiral gears, for the purposes specified.
75. In testimony whereof, I have signed my name to this specification, in the presence of two subscribing witnesses.
